(57) **CLAIM**

The ornamental design for a volatile dispenser, as shown and described.

DESCRIPTION

In a preferred embodiment the nature of this product is an air treatment dispenser suitable to hang on a person's belt, pocket or other clothing item and dispense insect repellents (e.g. mosquito repellent).

FIG. 1 is a right, top, frontal perspective view of a volatile dispenser embodying our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a right, top, frontal perspective view of a second embodiment of our new design;

FIG. 9 is a front elevational view thereof;

FIG. 10 is a right side elevational view thereof;

FIG. 11 is a left side elevational view thereof;

FIG. 12 is a top plan view thereof;

FIG. 13 is a bottom plan view thereof; and,

FIG. 14 is a rear elevational view thereof.

The broken line representations of various parts in FIGS. 8-14 are for purposes of illustration only and form no part of the claimed design.
